United States Patent Office.

HENRY VAN KEUREN, OF JERSEY CITY, NEW JERSEY.

Letters Patent No. 106,433, dated August 16, 1870.

IMPROVEMENT IN PUMPS.

The Schedule referred to in these Letters Patent and making part of the same.

To all whom it may concern:

Be it known that I, HENRY VAN KEUREN, of Jersey City, in the county of Hudson and State of New Jersey, have invented and made a new and useful Improvement in Pumps; and the following is hereby declared to be a correct description of the same.

For canal-boats and barges a pump is extensively employed, made of sheet metal, such as tin, with a check-valve at the bottom, and a piston and valve, worked by a rod or handle. This same character of pump is also used in excavations, such as for sewers, drains, &c.

The valves of the pump frequently become obstructed by sand and foreign substances, and, in sewers, the sand is sometimes pumped, through carelessness, into the barrel of the pump, and, in lifting up the sheet-metal pump, with this accumulation, to empty the same out, the metal is often indented and broken, and the accumulation of water, while the pump is being put into condition, sometimes injures the work; but a more fruitful source of trouble arises from the fact that the sheet metal of the barrel is soldered direct to the ring that carries the valves, hence, the pump has to be unsoldered or cut when there are any repairs to be made to the valve, and sometimes when only necessary to clean said valves.

My invention consists in an auxiliary ring, soldered to the sheet-metal barrel of the pump, and provided with a screw-thread, that receives the base of the pump containing the valves, so that the base can be

unscrewed from the pump with facility, to give access to the valves, for cleaning or replacing the valves, or for cleaning the barrel, thereby lessening the risk of injury to the pump-barrel, avoiding the unsoldering or cutting heretofore usual, and avoiding the difficulties heretofore liable to arise when the pump becomes useless.

In the drawing—

Figure 1 is a vertical section of the said ring, base, and valves, and

Figure 2 is a sectional plan of the same.

The barrel *a* of the pump is made of sheet metal, such as tin, soldered to the auxiliary screw-ring *b*; and *c* is the base of the pump that screws into the ring *b*, and is provided with the legs or supporting projections 2 2, valve-seats 3 4, and valves *e*.

It will now be understood that the base of the pump can be unscrewed and removed with facility, for cleaning the valves or barrel, and that new valves can be introduced by removing the screw 5 and bar 6.

I claim as my invention—

The auxiliary ring *b*, soldered to the sheet-metal pump-barrel, and combined with the base *c* and valves *e*, constructed and arranged substantially as and for the purposes set forth.

Signed this 31st day of May, A. D. 1870.

HENRY VAN KEUREN.
